UNITED STATES PATENT OFFICE.

FRANK CONRAD, OF PITTSBURGH, PENNSYLVANIA, ASSIGNOR TO WESTINGHOUSE ELECTRIC AND MANUFACTURING COMPANY, A CORPORATION OF PENNSYLVANIA.

STARTING MECHANISM FOR INTERNAL-COMBUSTION ENGINES.

1,413,829.

Specification of Letters Patent. Patented Apr. 25, 1922.

Application filed December 26, 1913. Serial No. 808,783.

To all whom it may concern:

Be it known that I, FRANK CONRAD, a citizen of the United States, and a resident of Pittsburgh, in the county of Allegheny and State of Pennsylvania, have invented a new and useful Improvement in Starting Mechanism for Internal-Combustion Engines, of which the following is a specification.

10 My invention relates to starting mechanisms for internal combustion engines and particularly to such mechanisms as embody electric motors.

15 My invention has for one of its objects to provide a simple and effective means whereby a starting motor may be automatically connected to and disconnected from the shaft of an internal combustion engine.

20 A second object of my invention is to provide a starting mechanism that operates without excessive shocks incident to the automatic engagement of a motor-driven pinion and the fly wheel gear.

25 As heretofore constructed, mechanisms of this character must, ordinarily, be connected to the engine shaft by manually operated means or, if automatic means be employed, additional structure is necessary which adds materially to the cost of manufacture and to 30 the weight and complexity of the starting device.

35 My invention comprises a motor having an armature shaft which is operatively connected to a screw threaded shaft to coact with a correspondingly threaded gear wheel to shift the latter into and out of mesh with a gear wheel on the engine shaft. A friction clutch connects the motor shaft to the screw-threaded shaft. Magnetic means are 40 employed to supplement the inertia of the threaded gear wheel to produce relative movement between the gear wheel and the threaded shaft.

45 In the accompanying drawings, Fig. 1 is a side view, partially in elevation and partially in section, on line I—I of Fig. 3, of an electric motor with my invention applied thereto. Fig. 2 is a sectional view illustrating an electromagnet for holding the 50 threaded gear wheel, the electrical connections being shown diagrammatically. Fig. 3 is an end view of a portion of an engine

having the starting mechanism attached thereto.

An electric motor 1 has an armature shaft 55 2 that is provided with a pinion 3. A gear wheel 4, which meshes with the pinion 3, is mounted upon a shaft 5 for frictional engagement with two flanged collar members 6 and 7 that are mounted upon the shaft 5. 60 The collar members 6 and 7 are provided, upon their adjacent faces, with friction material 25 to engage the gear wheel 4. The collar member 7 is slidably mounted upon the shaft 5 and is normally pressed 65 against the gear wheel 4 by a spring 8. The collar member 6 is screw-threaded upon the shaft 5 to provide a means for adjusting the degree of tension of the spring 8 and thereby controlling the amount of friction 70 for preventing relative movement of the several parts. The clutch is so adjusted that it will transmit, without yielding, the torque necessary to actuate the engine under normal conditions, but will yield temporarily 75 in case of sudden application of excessive torque such as may occur upon the automatic engagement of coacting gear wheels of the starter and the engine. The shaft 5 is provided with a threaded portion 80 9 upon which is mounted a pinion 10 that is correspondingly threaded to coact with the shaft. The pinion 10 is provided with a collar member 11 having a cylindrical shoulder portion 12 to be engaged by spring 85 clips 13 that are mounted between the collar member 6 and the spring 8. The collar member 11 is provided upon its periphery with four oppositely disposed pole pieces 14. An electromagnet 15, Fig. 2, comprising 90 a core member 16 that spans a pair of adjacent pole pieces 14 and a coil 17 that is in series with the motor armature, coacts with the pole pieces 14 to hold the pinion 10 against rotative movement and thereby 95 produce an axial movement of the pinion 10 on the shaft 5 when the latter rotates. The clips 13 tend to rotate the pinion 10 with the shaft 5 but the magnet 15 exerts the stronger force when the parts are stationary, as will be later described. A housing 18 100 partially encloses the mechanism above described and provides bearings for the shaft 5.

Referring particularly to Fig. 3, a gas

engine 19, only a portion of which is shown, comprises a crank case 20, a shaft 21, and a fly wheel 22 that is provided with gear teeth 23 to coact with the pinion 10. A bracket 24, which is attached to the under side of the crank case 20, supports the motor 1 and its connected mechanism.

When the circuit of the motor 1 is closed through any suitable electrical connections, 10 as, for example, the circuit of Fig. 2, the coil 17 is energized to cause the core member 16 to attract that pair of pole pieces 14 which are nearest the same to prevent the rotation of the pinion 10. The armature shaft 2 will rotate the shaft 5 through the pinion 3 and gear wheel 4. The pinion 10, the rotation of which is opposed by the magnet 15 and by its own inertia, will be advanced outwardly along the shaft 5 by 20 means of the screw threads until it meshes with the fly wheel gear teeth 23 and engages a collar member 26 that acts as a stop to limit its endwise movement.

The teeth of the pinion 10 are rounded 25 or beveled at their outer ends as indicated at 27 in order to facilitate the meshing of the respective gear teeth. It is only necessary that the magnet hold the pinion for a very brief interval because of the small 30 movement required to bring the gear teeth into engagement. Because of the high speed attained by the motor at the point of meshing the pinion 10 with the fly wheel gear teeth 23 and of the relatively high inertia 35 of the engine, a severe shock would occur when the pinion 10 reaches the collar 26 if the driving connections were suddenly established through a rigid mechanism. The frictional connection of the gear wheel 4 40 with the shaft 5 allows a temporary relative movement between these parts so that a shock is avoided.

During the temporary slipping of the friction clutch, sufficient torque is transmitted to overcome the inertia of the engine. 45 This torque is greater than that required under normal conditions. As soon as the engine has acquired such speed that the torque transmitted by the clutch is within 50 a predetermined value, relative movement between the clutch parts ceases. The clutch may be so adjusted that the values of the torques transmitted under the conditions above described are well within the limits 55 required to operate the engine.

When the engine starts under its own power, the fly wheel rotates at a speed sufficiently high to cause pinion 10 to overrun the shaft 5 and to be disengaged from the 60 fly wheel gear teeth 23 as it travels inwardly along the shaft. When the pinion approaches the end of its path of movement in this direction, the clips 13 engage the shoulder portion 12 to carry the pinion 10 65 with the shaft 5 and thereby prevent the

pinion from again being thrown into mesh with the fly wheel 22 while the latter is rotating at a high speed.

When the shaft 5 and the pinion 10, with its pole pieces 14, are rotated at a high rate 70 of speed, the magnet 15 has a comparatively slight retarding effect upon the pinion 10, relatively to the combined magnetic force and inertia in starting and the spring clips 75 13 will retain the pinion in its inoperative position, as illustrated. While the operator will ordinarily open the motor circuit almost immediately after the engine starts, a safety device is essential in order to provide for any delay or neglect on the part of the 80 operator.

In case of backfire of the engine, the friction clutch yields and damage to the motor or associated parts is prevented.

It will be noted that I have provided a 85 mechanism which is entirely automatic in its operation to operatively connect a starting motor to the shaft of an internal combustion engine and to disconnect the same when the engine starts under its own power. 90

I claim as my invention:

1. In a starting mechanism, the combination with a gear wheel, and a pinion having pole pieces, of a shaft having a screw-threaded connection with said pinion, and a magnet coacting with said pole pieces.

2. In a starting mechanism, the combination with a gear wheel, and a pinion coacting therewith, of means for shifting said pinion into and out of mesh with said gear wheel, said means comprising a spirally threaded shaft and electromagnetic means for opposing rotation of said pinion.

3. In a starting mechanism, the combination with an engine shaft, and a gear wheel connected thereto, of a motor having a shaft, a spirally threaded shaft operatively connected to said motor shaft, a pinion on said threaded shaft for coacting therewith, and a magnet for opposing rotation of said pinion.

4. In a starting mechanism, the combination with a gear wheel, and a pinion having pole pieces, of a shaft having a screw-threaded connection with said pinion, an 115 electric motor operatively connected to the said shaft, and an electromagnet coacting with said pole pieces and comprising a coil in circuit with said motor.

5. In a starting mechanism, the combination with a gear wheel, of a shaft having spiral threads, a motor for driving said shaft, a pinion on said shaft having coacting spiral threads, and means comprising an adjustable friction clutch for yieldingly 125 preventing relative movement between said shaft and said motor except under predetermined conditions.

6. In a starting mechanism, the combination with an engine shaft, and a gear wheel 130

connected thereto, of a motor having a shaft, a screw-threaded shaft, means comprising a friction clutch for connecting said screw-threaded shaft to said motor shaft and a 5 pinion on said screw-threaded shaft for co-acting with the gear wheel.

7. In a starting mechanism, the combination with an engine member, a motor and a shaft driven thereby, of a driving member 10 movable longitudinally of said shaft and rotatable therewith to drive said engine member, and a friction clutch between said motor and said driving member.

8. In a starting mechanism, the combination with an engine member, a motor and a shaft driven thereby, of a driving member 15 movable longitudinally of said shaft and rotatable therewith to drive said engine member, and a friction clutch between said 20 motor and said shaft.

9. In a starting mechanism, the combination with an engine member, a motor and a shaft driven thereby, of a driving member 25 movable longitudinally of said shaft and rotatable therewith to drive said engine member, and a friction clutch for permitting relative movement between said motor and said driving member, and adjustable means for controlling the members of said 30 clutch.

10. In a starting mechanism, the combination with an engine member, a motor and a shaft driven thereby, of a driving member, means whereby relative movement between 35 the motor and the driving member actuates said driving member into engagement with said engine member and a friction clutch

between said motor and said driving member for permitting relative movement therebetween under predetermined conditions. 40

11. In a starting mechanism, the combination with an engine member, a motor and a shaft, of a pinion, carried by said shaft for longitudinal movement thereon and rotary movement therewith, said pinion coacting 45 with said member, and a friction clutch for operatively connecting said motor and said shaft, said clutch being so adjusted that it will transmit without yielding the torque necessary to rotate the engine under normal 50 conditions, but will yield when the torque applied to the engine exceeds a predetermined value.

12. In a starting mechanism, the combination with an engine member, a motor and a shaft, of a pinion carried by said shaft for longitudinal movement thereon and rotary movement therewith, said pinion coacting 55 with said member, and a friction clutch for operatively connecting said motor and said 60 shaft, said clutch being so adjusted that it will yield when the torque applied thereto exceeds a predetermined value and, when yielding, will transmit a torque greater than that required under normal conditions, 65 whereby it will cease to yield when normal conditions are restored.

In testimony whereof, I have hereunto subscribed my name this 19th day of Dec. 1913.

FRANK CONRAD.
